UNITED STATES PATENT OFFICE.

OLIVER E. BECKER, OF OAK PARK, ILLINOIS.

ELECTRICAL-BRUSH CONNECTION AND METHOD OF MAKING THE SAME.

1,288,474.

Specification of Letters Patent. Patented Dec. 24, 1918.

Application filed April 13, 1918. Serial No. 228,377.

To whom it may concern:

Be it known that I, OLIVER E. BECKER, a citizen of the United States, residing at Oak Park, in the county of Cook and State of Illinois, have invented a certain new and useful Improvement in Electrical-Brush Connections and Methods of Making the Same, of which the following is a full, clear, concise, and exact description, reference being had to the accompanying drawings, forming a part of this specification.

My invention relates to brushes for electrical machinery and method of and means for making the same.

15 More particularly my invention relates to gauze brushes, that is, brushes made of interwoven or interlaced wires, and the method of and means for attaching the leads or pigtails to the same.

20 As is well known to those skilled in the art, the body of the gauze brush is generally constructed by rolling or winding a sheet or strip of wire gauze upon a mandrel and then removing the roll from the mandrel 25 and pressing or rolling the gauze into suitable prismatic form. This is set out in the patent to Guttman, No. 599,781.

The general practice of finishing the gauze brush and attaching the lead or pigtail has 30 heretofore consisted in dipping the upper part of the brush in tin or solder to fill the parts of the same for holding the form of the brush and for forming a suitably rigid portion for the attachment of the lead or 35 pigtail. A hole is then drilled into the upper part of the brush and the lead or pigtail, which is usually made of stranded cable or woven ribbons, is then soldered into said hole.

40 I have found this to be unsatisfactory for a number of reasons. One objection is the amount of labor involved. A further objection has been due to the fact that heating of the brush may result in loosening of the 45 lead from the body of the brush, and at any event it may easily result in increasing the contact resistance between the lead and the body of the brush. A further and more frequently encountered objection is the tendency of the solder to be taken up by the 50 cable or lead by the capillary action of the solder upon the strands of the cable, thereby rendering the lead stiff. If the lead becomes filled with solder it becomes practically rigid and tends to interfere with the

action of the brush in the holder and may easily be broken off by bending.

My invention aims primarily to overcome these objections by an improved brush and lead construction and method of making the 60 same. A further object is to provide means for practising the method of manufacture. According to my invention I take the brush body after it is roughly formed and compress the same into suitable shape, leaving 65 a part of the brush body where the lead is to be attached in a relatively loose condition. I then drive a spreading punch in the form of a pointed pin into the uncompressed portion to form a hole, somewhat according 70 to the manner in which an awl is forced into a piece of leather or fabric. The spreading punch preferably does not form the hole by shearing or punching, in the sense of driving the metal downward, but 75 preferably spreads the fibers, and incidentally tearing the same apart laterally. This leaves an enlarged portion in the body of the brush about the hole. The body of the brush with the hole formed in the enlarged 80 portion may then be dipped to fill the top surface with solder so that the brush may better retain its form. This latter step may, under certain conditions, be omitted. Thereafter the lead or pigtail is inserted in the 85 hole and the body of the brush about the hole is then crushed together upon the end of the lead or pigtail.

The crushing of the body of the brush upon the pigtail causes the individual fibers 90 or wires of the gauze to grip the individual fibers of the lead or pigtail very firmly. Thus the intermixing and interlacing of the strands of the wire or gauze on the strands of the flexible lead, forms an ideal gripping 95 engagement for holding the pigtail or lead to the body of the brush.

In practice I perform the operation of shaping the body of the brush and forming the hole in the body of the brush in one 100 operation in suitable dies in a punch press.

A lead is then inserted by hand. The steps of closing the hole upon the lead and bringing the brush to final form is then performed by another die operation. Thus not 105 only do I provide a less expensive method of constructing the finished brush, but I provide also an improved and better article and further I provide a convenient means for performing certain steps of the method 110

above outlined. This method may be practised with plain gauze brushes or with the lubricated brush described and claimed in patent to Schweitzer, No. 1,228,484.

5 In order to acquaint those skilled in the art with one particular manner in which the invention may be carried out, I shall now describe, with the aid of the accompanying drawings, the apparatus which I employ, 10 the steps which I perform and the structure of the brush secured thereby.

In the accompanying drawings, Figure 1 is a vertical sectional view taken on the line 1—1 of Fig. 2 of the die mechanism employed to form the brush;

15 Fig. 2 is a horizontal sectional view taken on the line 2—2 of Fig. 1, showing certain of the parts in plan;

20 Fig. 3 is a vertical section taken at right angles to the section of Fig. 1 on line 3—3 of Fig. 1;

Fig. 4 is an elevational view of the finishing die mechanism;

25 Fig. 5 is a perspective view of the roll of gauze prior to its formation into rectangular form;

30 Fig. 6 illustrates the roll of gauze as compressed into rectangular prismatic form, with the hole and enlargement formed at one corner;

Fig. 7 illustrates the body of the brush after the operation of dipping the top of the brush in melted metal;

35 Fig. 8 is a sectional view of the body of the brush showing the manner of securing the union between the fibers of the gauze and the strands of the lead;

40 Fig. 9 is a perspective view of the body of the brush after the same has been dipped and the pigtail or lead inserted in the hole;

Fig. 10 shows the dies for corrugating the sides of the gauze brush, and

45 Fig. 11 is a perspective view of a brush with corrugated sides for strengthening the outer layer against spreading.

50 As previously explained, the first step in producing a brush is to form a roll of gauze by rolling a strip or sheet of the same upon a mandrel to produce a rough roll as shown in Fig. 5.

This feature is old and is explained in the prior patents above referred to. The roll of gauze 1, which later forms the body of the brush, is placed in the die mechanism shown in Figs. 1, 2 and 3 and is there brought to form and is punched by means of a spreading punch by the mechanism which will now be described. The roll 1 may be given a preliminary shaping operation before placing in the die mechanism shown in Figs. 1, 2 and 3 or it may be placed in the die mechanism in the rough. In Figs. 1, 2 and 3 I have shown the roll 1 as having a preliminary shaping to bring it to substantially rectangular form, although as

above explained, it is not necessary. The roll 1 is rested against a back plate member 2, this back plate being bolted by means of the bolts or cap screws 3 upon the back frame member 4, mounted upon the main frame plate 5. The main frame plate 5 in turn is supported upon a suitable pillow block 6 of any desired weight and configuration.

70 The back plate 2 has a pair of stop members or projections, 6 and 7. Movable end die members 8 and 9, which are suitably cut out to receive the projections 6 and 7 as shown at 10 and 11, are guided between the back plate 2 and the front plate 12. The end die members 8 and 9 are provided with projecting ends 13 and 14 which are adapted to engage the end parts of the roll of gauze 1. At their rear ends the end die members 8 and 9 rest against the stops 15 and 16, which stops are rigidly connected to the main frame plate 6. The retracting rods 17 and 18 are slidably mounted in the blocks 15 and 16 and at their inner ends are threaded to, or otherwise secured to the end die members 8 and 9. Suitable springs 19 and 20 are interposed between the blocks 15 and 16 and the head members 21 and 22 on the rods 17 and 18, so that when the die members are moved inwardly to operate 85 upon the roll of gauze 1, they may be automatically retracted by means of the springs 19 and 20.

90 A front die member 23, guided in a suitable frame 24, is adapted to move in and press upon the front side of the roll of gauze 1. A retracting rod or plunger 25 and springs 26, serve to retract automatically the die member 23, as will be set out 95 below.

100 A guiding plate 27 extends over the die members 8 and 9 and also extends over the side die members 23 to prevent accidental disengagement of the die members by upward motion. This guiding plate 27 110 normally extends across the die member 23, but is shown as broken away in the figures for the sake of clearness. The guide plate 27 is secured on the top of the front plate 12.

115 It will be noted that the die members 2, 8 and 23 have recesses 28, 29 and 30 formed in the same so that the roll of gauze 1 may spread into the same to form an enlargement. This is for the purpose of permitting the gauze to be spread to form a hole in 120 the same for attaching the lead as will be described later.

125 The end die members 8 and 9 are adapted to be moved inward by the vertical cam pieces or punches 31 and 32, which are fastened in the head member 33. The head member 33 is connected in the end of the plunger of the punch press, as is well understood by those skilled in the art. The vertical cam or punch members 31—32 pro- 130

vided with the camming shoulders 34 and 35, these shoulders being adapted to engage the tapered surfaces 36 and 37 on the end die members 8 and 9 to force the same toward each other when the punch members 31 and 32 descend.

The front die member 23 is similarly provided with a shoulder 38 adapted to be engaged by the shoulder 39 of the vertical 10 cam or punch member 40, which is also fastened in the head member 33.

The timing of these punches is such that the punch 40 preferably closes in its die member 23 against the body 1 first. The 15 end punches 31 and 32 then close in the end dies 8 and 9 to compress the roll of gauze 1 into substantially finished shape and size with the exception of the enlargement formed in the recesses 28, 29 and 30 of the 20 adjacent die members. Thereafter the roll of gauze is operated upon by a spreading punch 42, which consists of a short pointed pin fastened in the bar 43. The bar 43 is in turn secured by means of a suitable shank 25 44 in the head member 33.

The roll of gauze 1 is thus transformed into the formed brush body 45, which has an enlargement 46 to receive the metal of the gauze, which is spread apart or moved 30 laterally by the formation of the hole 47. It is to be noted that the opening 47 extends only a short distance down into the body of the brush and also the enlargement 46 extends down only a short way.

35 Thereafter the top of the brush body 45 is dipped in tin or solder to unite the upper strands of the gauze, as indicated at 48 in Fig. 7. Thereafter the stranded lead or pigtail 49, the upper end of which may be 40 attached to a suitable clip 50, is inserted in the opening 47 and the body of the brush with the pigtail or lead 49 in place, is then placed in a suitable closing die 51 and is pressed by the plunger 52 to compress the 45 material of the body of the brush upon the lead 49 and at the same time forming the brush to finished size. It is to be noted that the gauze of the brush may be formed with the fibers thereof running parallel with the 50 edges of the finished brush, or may run diagonal thereto, the resulting brush being securely gripped to the lead by the mechanical action alone.

It is to be noted that the spreading punch 55 42 tends to spread and may break some of the fibers of the gauze and when the gauze is compressed about the lead, these ends form effective gripping fingers for engaging the strands of the lead 49 so that a secure fastening is provided.

I contemplate the use of plain gauze or lubricated gauze of the character set out in the prior patent to Schweitzer above mentioned.

65 The body of the brush may be treated as

set out in my co-pending application, Serial Number 221,665, filed March 11th, 1918, to prevent spreading of the layers of gauze and fraying of the ends. I have also discovered that the brush may be reinforced by 70 mechanical formation, as shown in Figs. 10 and 11. By means of the die 54 and the punch 55, indentations or corrugations 56 may be formed in the material of the brush to provide mechanical reinforcing ribs. 75 This corrugation of the sides may be secured at the time that the brush is formed in the operations illustrated in Figs. 1, 2 and 3, or it may be performed in a closing operation when the material of the brush is compressed about the lead 49 as shown in Fig. 10.

I do not intend to be limited to the precise details of construction shown or described and I intend that certain modifications of the order of practising the various steps, such as will be apparent at once to those skilled in the art, are contemplated within the scope of the appended claims.

I claim:

1. The method of uniting a gauze brush with its lead, which consists in compressing the body of the brush to approximately final size and shape, spreading apart the metal of the body to form a hole in the same, inserting a portion of the lead into said hole and closing the hole upon the lead by pressure.

2. The method of uniting a lead on the body of a gauze brush, which consists in thrusting a spreading punch into a portion of the brush to spread the wires of the gauze apart sufficiently to form an opening to receive the end of the lead, inserting the end of the lead in said opening, and closing the opening upon the lead by pressure.

3. The method of uniting a flexible lead to the body of a gauze brush, which consists in thrusting a spreading tool into a portion of the brush to spread the wires of the gauze apart sufficiently to form an opening to receive the end of the lead, filling the portion of the brush adjacent the opening with suitable metal, inserting the end of the flexible lead in said opening, and closing the opening upon the lead by pressure.

4. The method of uniting a flexible lead and the body of a gauze brush, which consists in compressing and dipping the body of the brush, except that point adjacent to 120 where the lead is to be connected, opening an aperture in the body of the brush where the lead is to be connected, then inserting a flexible lead in said aperture, and closing the aperture upon the lead by mechanical pressure.

5. The method of uniting a gauze brush with a flexible lead, which consists in spreading apart the fibers of the gauze at the point where the lead is to be connected, inserting 130

- the end of the flexible lead in said opening formed by spreading, and crushing the material of the gauze brush upon the end of the flexible lead to form a secure connection 5 between the two.
6. A gauze brush and lead comprising a gauze body and a flexible stranded lead projecting into said gauze body, said lead being gripped mechanically by the gauze.
- 10 7. A brush and lead comprising a metallic gauze brush body and a stranded flexible lead projecting into said body, the strands of the gauze being broken about said lead and having their ends thrust into gripping engagement with said lead.
8. The method of uniting a flexible lead to the body of a gauze brush which consists in compressing the body of the gauze brush, forming an aperture in the top of the body large enough to permit ready insertion of 20 the end of the flexible lead, inserting the end of the lead in said aperture, compressing the body of the brush to final form and simultaneously closing the sides of the aperture upon the lead to grip the same securely. 25

In witness whereof, I hereunto subscribe my name this 9 day of April A. D. 1918.

OLIVER E. BECKER
